a corporation of New York

Application October 2, 1934, Serial No. 53,456

To all whom it may concern:

Be it known that I, REBECCA SHAPIRO MARANISS, a citizen of the United States, residing at No. 65 Central Park West, in the city of New York, county of New York, and State of New York, have invented a new, original, and ornamental Design for a Textile Fabric or the like, of which the following is a specification, reference being had to the accompanying drawing, forming a part thereof.

The figure is a plan view of a textile fabric showing my new design.

The area within the dot and dash lines shows

one complete unit of the design. The repeats are arranged in vertical rows and adjacent vertical rows are one half a complete unit offset so that the angle of the complete unit indicated by letter A corresponds with angle A¹ of one of the repeats in an adjacent vertical row.

I claim:

The ornamental design for a textile fabric or the like as shown and described.

In testimony whereof I have signed this specification.

REBECCA SHAPIRO MARANISS.
